UNITED STATES PATENT OFFICE.

SAMUEL E. HORNER, OF SWARTHMORE, PENNSYLVANIA.

DESIGN FOR A SINK.

SPECIFICATION forming part of Design No. 23,632, dated September 4, 1894.

Application filed July 7, 1894. Serial No. 516,854. Term of patent 14 years.

To all whom it may concern:

Be it known that I, SAMUEL E. HORNER, a citizen of the United States, residing at Swarthmore, in the county of Delaware and State of Pennsylvania, have invented and produced a new and original Design for Sinks, of which the following is a specification, reference being had to the accompanying drawings, illustrative of the same.

- Figure 1 is a view in perspective of a sink embodying my design, and Fig. 2 a central, vertical, sectional, elevation of the same.

My invention relates to sink structures usually made as basin-like receptacles, of metal, of quadrangular plan, having a horizontal or practically horizontal bottom, and outwardly inclined or flaring end and side walls.

The leading characteristics of a sink embodying my design are,—that its rear wall is made vertical or perpendicular to the plane of the bottom of the structure;—that said rear wall is extended to a height considerably

above that of the front and side walls,—and that said rear wall embodies an outwardly bellied concavo-convex portion forming a recess behind the rear wall which recess is open as to its lower end but closed as to its upper end.

In the accompanying drawings, A is the sink, having the bottom a and the inclined front wall a^2 and side walls a' and a^3 , and B is the vertical rear wall, having the boxing or concavo-convex portion, b.

What I claim is—

The design for a sink substantially as herein shown and described.

In testimony that I claim the foregoing as my invention I have hereunto signed my name this 25th day of June, A. D. 1894.

SAMUEL E. HORNER.

In presence of—

J. BONSALL TAYLOR,
F. NORMAN DIXON.
